CONTAINER FOR PASTE, HOLDER THEREFOR, AND COOPERATIVE COMBINATION BRUSH AND COVER FOR USE THEREWITH

Noel S. Florence, Brooklyn, N. Y.

Application October 16, 1948, Serial No. 54,850

7 Claims. (Cl. 15—258)

1

This invention relates to a combination container for paste or the like and a brush for applying the paste, a portion of the brush serving as a cover for the container, when the device is not in use.

One object of this invention is to provide a combination brush and paste box in which a portion of the back of the brush, is made to serve as a tight fitting cover for the paste box, when the latter is not actually in use.

Another object of this invention is to provide a device of the type just described in which there is provided an ancillary handle serving as a convenient means of holding the paste box when in use, and also serving as a portion of the device which retains the brush in place upon the top of the box, so as to cover the latter when not in use.

Still another object of this invention is to provide a device of the type described in which an empty paste box may easily be discarded and replaced by a full box.

Yet another object of this invention is to provide a combination brush and cover which can be expeditiously placed upon a box of paste, so as tightly to seal the same, without the need of tightening screws or the like.

A further object of this invention is to provide a device of the character described in which resilient means are provided for maintaining the cover portion of the brush and the top of the paste box tightly pressing against one another, so as to prevent undesired evaporation of liquid from the paste, when the device is not in use.

A still further purpose of this invention is to provide a combination brush and paste box, wherein a recessed portion of the back of the brush is designed to function as a cover for the box, when not in use, and in which such recess is provided with one or more resilient sealing rings, so that exact parallelism between the cover and the box is not essential in order to secure an air-tight seal.

Still another purpose of this invention is to provide a combination device of the character above described, in which the sealing of the paste box by the portion of the handle serving as a cover can be readily accomplished without the need of using more than one hand, is firmly maintained without the need of fastening screws or the like, and in which it is possible to disengage the box and the cover, when desired, quickly and easily.

Still further objects and advantages of this invention will be apparent to those skilled in the art from the following specification and from the hereunto annexed drawings, in which:

2

Figure 1 is a side elevation of one form of the device of the present invention, the two major elements being shown separated for purposes of clarity, and the handle being partly broken away to show the sealing cover;

Figure 2 is a cross-sectional view of the clamping portion of the handle, taken upon the line 2—2, of Figure 1;

Figure 3 is a plan view of one form of box-holder;

Figure 4 is a plan view of an alternative form of combination brush and cover; and

Figure 5 is an alternative form of box-holder designed to be used with the brush of Figure 4.

Referring now to Figures 1 to 3 inclusive, the paste box is shown at 10. It is provided with a peripheral groove 11, near the upper edge of the box. The box-holder includes a circular portion 12, which is made of such diameter that it can be slipped over the upper edge of box 10, after a clamping member 13 has been slid along the central constricted portion 14 of the holder, until it has reached the portion 15, where the holder is again made wide enough so as to serve conveniently as a gripping portion for the hand. When the clamp 13 is placed in this position, the resiliency of the material of which the holder is constructed, which may be metallic wire or the like, or plastic material having the requisite degree of resiliency, allows the diameter of the portion 12 to be slightly increased, so that it can be pushed into position over the edge of the box, until it snaps into position within groove 11, as shown in Figure 1. The holder is maintained firmly in position by sliding clamp 13 to the position shown in Figure 3.

The handle 20 of the brush element may be constructed of any shape suitable for gripping by the hand, and of any suitable material, such as plastic or a metal which will not easily oxidize or corrode. Near one end of the handle are provided, upon one side thereof, the usual bristles 21. These may be of any material and shape suited to be used with the paste employed in a given instance. The other side of the handle, at a point opposite the bristles, is recessed as indicated at 22, so that flange 23 can extend over the upper portion of the paste box for a limited distance, the contour of the recess corresponding to the contour of the top of the paste box. In the embodiment of this invention here shown, the paste box has been indicated as being circular. However it is to be understood that other shapes such as square, triangular or other polygonal forms may be employed without altering the general character or operation of the invention. In case

of any particular shape of box, the portion 12 of the box-holder and the recess 22 of the brush handle will merely be made of a contour corresponding to that exhibited by the box. The upper end of recess 22 is lined with a resilient ring or washer 24, of rubber or other similar material. This allows an air-tight seal to be made between the upper edge of box 10 and the cover portion of the brush.

For proper maintenance of the seal of the box when not in use, brush 20 is provided with a locking portion 25, as shown in Figure 2. This portion is slotted at 26, and the curvature of portions 14 and 15 of the box-holder is made such that portion 15 will contact the brush handle at approximately the same time that the upper rim of box 10 contacts sealing washer 24, while at that same time portion 14 of the holder will not quite reach slot 26. Manual pressure is then employed to squeeze portion 14 and brush 20 toward one another, until portion 14 can be slid within slot 26, thus resiliently locking the two elements into box-sealing position. The locking action afforded by thus placing the handle and box-holder under mutual tension forcing them together, serves to maintain the paste tightly covered, an air-tight seal being assured by the action of washer 24. If the handle of brush 20 be gripped by the hand, and a plurality of fingers be extended so as to engage portion 14 of the box-holder upon the slotted side of lock 25, the pressure exerted by these fingers will suffice to force the holder within the lock, so that only one hand need be employed. In a similar fashion, a single hand suffices to release the lock by pushing portion 14 without slot 26. However it may sometimes be more convenient to use both hands for these operations.

In Figure 4 is shown the bristle-carrying side of a brush provided with an alternative form of lock. This comprises an H-shaped aperture 30, which is preferably tapered so as to be widest on the same side as the recess of the handle. The function of this aperture is hereinafter explained.

Figure 5 shows an alternative form of box-holder, having the same loop 12 already described in connection with Figure 3. However the handle portion has each side provided with a loop 31, both loops extending upwardly and having a width correspondent to that of the H-shaped aperture 30 of the brush handle. Upon placing the fingers in the loops 32 provided at the extremity of each handle of the holder, and squeezing the two handles together, both loops 31 can be inserted within the cross-bar portion of aperture 30, so that the loops extend completely through the handle of brush 20. When the manual pressure is removed from loops 32, loops 31 will tend to separate, due to the resiliency of the material of which the box-holder is formed. This will cause these loops 31 to spread apart and lock over the two projections in the recessed portion of aperture 30, thereby locking the holder and the brush together in a fashion which will secure the same results as already recited in connection with the form of Figures 1-3.

While I have shown and described certain embodiments of this invention, it is to be understood that many variations and alterations thereof will be apparent to those skilled in the art and may be made without departing from the scope of the instant invention, which is defined only by the hereunto appended claims.

Having now set forth and described my invention, what I claim and desire to secure by Let-

ters Patent of the United States of America is as follows:

1. A combined paste box and brush, including an open box externally peripherally grooved near the upper lip thereof, a brush of the unilaterally setaceous type, having a recess upon the side of the handle thereof opposite the bristles thereof, said recess being of such size and so formed as snugly to fit over and to cover said box, a resilient

box handle fitting in said groove and extending in a generally parallel position alongside the brush handle, and locking means into which a portion of said box handle can be forced by lateral flexing thereof, so as to hold tightly and resiliently together said two handles, for at least a portion of their respective lengths, whereby said recess acts as a cover for said box when said two handles are held firmly but resiliently in approximation to one another, by said locking means, said cover and said box being thereby under continuous stress urging them into close contact with one another, when said two handles are locked together.

2. A combination article according to claim 1, in which said box handle comprises a resilient wire bent at one end thereof into a shape adapted snugly to fit within said groove, and discrete and tangible clamping means situated externally upon the portion of the handle of said brush facing said wire, and adapted to receive resiliently therein a portion of said wire, whereby said two handles are resiliently forced towards one another.

3. A combination article according to claim 1, in which said box handle comprises a resilient wire, adapted snugly to fit within said groove of said box and bent into two substantially parallel inverted U-shaped portions near the middle thereof, the handle of said brush being provided with an H-shaped recess opposite said U-shaped portions of said wire, whereby said U-shaped portions may be lockingly but resiliently engaged within said H-shaped recess, so as to lock together said two handles.

4. In combination, a paste box provided with an elongated resilient handle and a dauber brush of the unilaterally setaceous type, also provided with an elongated handle, both said handles extending substantially parallel to one another, and locking means subsisting in tangible form upon at least one of said handles and operative upon flexing of the box handle towards the brush handle, so as to allow a portion thereof to be held in flexed condition, whereby said resilient handle is placed under locked stress, and whereby said brush and said box are held and continuously forced into mutually resilient contact with each other.

5. A combination according to claim 4, in which a portion of the non-setaceous side of said dauber brush is formed of size and shape correspondent to those of the open side of said paste box, whereby the resilient holding in contact of said brush and said handle causes said shaped portion of the brush to be forced against said open side of said paste box, so that it functions as a firm and certain closure of said paste box.

6. A combination according to claim 4, in which said locking means comprises a slotted member, externally situated upon said brush handle, whereby a portion of said resilient box handle may be forced within the slot of said member, by flexing of said resilient handle towards the brush handle.

7. A combination according to claim 4, in which said locking means comprises two substantially

parallel inverted U-shaped members, formed integrally with said resilient handle and extending in a direction towards said brush handle, when the two handles are approximated, said brush handle being provided with a suitably shaped aperture into which said U-shaped members can readily enter by flexing of said resilient handle towards said brush handle, and also being provided with projecting body portions extending in the plane of the brush handle and transversely to the greater length thereof, into said aperture, whereby said U-shaped members may be locked with said projecting portions, so as to be locked within said aperture, after the force producing said lateral flexing has been terminated.
